No. 11, 1876

July 1, 1879

UNITED STATES PATENT OFFICE.

CHARLES L. BROWN, OF NEW YORK, N. Y., ASSIGNOR TO E. N. WELCH
MANUFACTURING COMPANY, OF FORESTVILLE, CONN.

DESIGN FOR CLOCK-CASE FRONT.

Specification forming part of Design No. **11,276**, dated July 1, 1879; application filed June 9, 1879.
[Term of patent 7 years.]

To all whom it may concern:

Be it known that I, CHARLES L. BROWN, of the city, county, and State of New York, have originated and produced a new Design for a Clock-Case Front, of which the following is a full, clear, and exact description, reference being had to the accompanying photographic illustration, making part of this specification.

The ordinary sash and dial form the central portion of the front, surrounding which sash the ground-work is ornamented by radial grooves, which form a ring, A. Bordering the ring A, and partly covering it, is a group of planets, stars, and moons, the latter in various forms, as shown. A scalloped-edge ornamental figure, B, pointed at the top, surmounts the front, the surface being covered with grooves radiating from a half-moon-shaped figure at the base of B, the corners of which are supported by new moons or convexo-concave figures, as shown. The base has a plain horizontal bar at the bottom, and a new-moon-shaped figure on each side, the upper point of which meets the ring A. A large star covers the middle portion of the base, and the ground-work of said base is ornamented by short horizontal and vertical grooves, arranged in squares, the whole forming a neat and attractive design, which I term the "Galaxy."

While I have described the ornamentation of the ground-work, it is evident that the same might be changed without changing the other features of the design.

I claim as my invention—

1. The design for a clock-case front, consisting, essentially, of a group of planets surrounding the sash and dial, substantially as described and shown.

2. The design for a clock-case front, consisting, essentially, of a group of planets surrounding the sash and dial, and a base the sides of which are formed of new-moon-shaped figures, substantially as shown and described.

3. The design for a clock-case front, consisting, essentially, of the ring ornamented by radial grooves, bordered by a group of planets, substantially as shown and described.

4. In a clock-case front, the design for the base, consisting of the bottom horizontal bar, the new-moon-shaped side figures, and the middle star, substantially as shown and described.

CHARLES L. BROWN.
